UNITED STATES PATENT OFFICE.

OSCAR I. JUDELSHON, OF BROOKLYN, NEW YORK.

STRIP-WINDING MACHINE.

1,267,080.

Specification of Letters Patent. Patented May 21, 1918.

Application filed October 31, 1916. Serial No. 128,672.

To all whom it may concern:

Be it known that I, OSCAR I. JUDELSHON, a citizen of the United States, and resident of New York city, borough of Brooklyn, in 5 the county of Kings and State of New York, have invented certain new and useful Improvements in Strip-Winding Machines, of which the following is a specification.

My invention relates to improvements in 10 machines for winding strips or webs of cloth or other fabric, commonly called spooling or reeling, objects of my invention being to wind the strips evenly back and forth along the spools; to provide for substantially even winding tension on the strips, irrespective of the diameter of the spools or 15 reels as they are being wound; to cause direct and accurate delivery of ironed strips, whether they are folded or unfolded, 20 directly from ironing rolls to the spools, and generally to simplify and improve machines of the character specified.

My invention comprises novel details of improvement and combinations of parts that 25 will be more fully hereinafter set forth and then pointed out in the claims.

Reference is to be had to the accompanying drawings forming part hereof, wherein;

Figure 1 is a front view of a winding machine embodying my invention;

Fig. 2 is a plan view thereof;

Fig. 3 is a section substantially on the line 3, 3, in Fig. 2;

Fig. 4 is a partly sectional view through 35 the spool or reel supporting and rotating spindle and its driving means;

Fig. 5 is an enlarged plan view of part of Fig. 4;

Figs. 6 and 7 are sections respectively on 40 the lines 6, 6, and 7, 7, in Fig. 5;

Fig. 8 is an enlarged end view illustrating a spool upon the winding spindle;

Fig. 9 is a section of the spindle having a core thereon;

Fig. 10 is an end view of heating roll 5 and its shield, and

Figs. 11 and 12 are sections of folded strips.

In the accompanying drawings the number 50 1 indicates the frame or bed of a machine, which may be supported in any suitable manner, as upon legs (not shown). At 2 is a driving shaft journaled in suitable bearings upon spaced uprights or standards 55 3 upon bed or frame 1. Ironing rolls for the strips to be wound are indicated at 4, 5.

The roll 4 is suitably secured upon shaft 2. The roll 5 is suitably secured upon shaft 6 journaled in bearings in the uprights 3. The boxes 7 having the bearings for shaft 6 60 may be adjustable in uprights 3, and normally spring pressed toward shaft 2 by springs 7, which may be adjusted to vary their tension in any well known manner. A pinion 8 secured on shaft 2, in mesh with a 65 gear 9 secured on shaft 6, enables rotation of roll or drum 5 at the same peripheral speed as that of roll 4. Shaft 2 may be rotated by a belt 10 (from a suitable source of power) passing over a pulley 11 secured on 70 shaft 2. Roll or drum 5 is shown hollow and adapted to be heated, for which purpose one or more gas burners 12 may enter the open end of said roll or drum, the pipe 13 supplying gas to said burners, a blue flame 75 preferably being used. At 14 is a shield supported upon shaft 6 and resting upon burner pipes 12, closing the open end of roll 5 at its upper portion (Fig. 10) to prevent the flame or heat from engaging strips passing around said roll. At 15 is a winding spindle located adjacent to roll 5 and around which the strips are to be wound, either upon a spool 16 or a core 17, to be mounted upon said spindle. At 18 is an arm having 80 a bore or bearing 18^a (Fig. 4) at or adjacent to its free end for rotatively supporting spindle 15. Arm 18 is adapted to rock and is mounted upon a rod or shaft 19 carried by the uprights 3. The arm 18 may be 85 loosely mounted on rod or shaft 19 which may be secured in standards 3 or said arm may be secured to said rod or shaft, the latter being journaled in standards 3. Arm 18 may be counterbalanced to any desired 90 extent by means of a weight or extension 18^b connected with said arm.

I provide means whereby spindle 15 may be frictionally rotated from a wheel or pulley 20. I have shown spindle 15 at one part rotative within a sleeve 21 that is rotatively mounted in bearing 18^a of arm 18, the wheel or pulley 20 being secured to said sleeve at one side of said arm, as by means of a screw 22 (Fig. 4). At 23 is a flange shown projecting from a hub 24, slidably mounted upon spindle 15, and adapted to frictionally coact with the adjacent face of wheel 20 for rotation by the latter. A friction washer or the like 25 of suitable material, such as leather or felt, may be interposed between wheel 20 and flange 23. Spindle 15 is shown provided

with a longitudinal groove 26 receiving a key, such as a screw 27, shown projecting from hub 24, whereby flange 23 will cause rotation of spindle 15, in different positions of adjustment of said flange along the spindle. A spring 28 shown coiled around spindle 15 and operating at one end against flange 23 and at the other end against an adjustable stop 29 on spindle 15 is adapted to cause flange 23 to coact with wheel or pulley 20 with frictional engagement. The stop 29 may be adjustable along spindle 15 by means of threads 30 on said spindle engaging the threaded bore of said stop, a screw 31 carried by said stop serving to retain the latter in adjusted positions on the spindle. A thrust bearing is shown between sleeve 21 and spindle 15, for which purpose I have shown antifriction balls 32 interposed between a raceway 33 shown formed in the face of the flange portion 15^a of spindle 15 and the race-way formed at the outer end of sleeve 21, as at its flange portion 21^a that opposes the adjacent side face of arm 18. The spring 28, in addition to maintaining a desired frictional engagement between wheel or pulley 20 and flange 23, serves to keep the raceway 33 against the anti-friction balls, whereby spindle 15 is rotatively maintained in the desired position for rotation by wheel 20. Since spindle 15 is rotative within sleeve 21 and since said sleeve is rotative within its bearing independent of the spindle, the rotation of the latter will not be affected by any pull of the belt on wheel or pulley 20, so that if the belt be adjusted tightly on said wheel it will not affect the free and independent rotation of spindle 15 on its bearing in sleeve 21. To prevent spindle 15 being pulled outwardly when the spool or reel is removed therefrom, I have shown a flange or collar *a* secured on the spindle within wheel 20, flange 23 and washer 25, and preferably normally spaced therefrom, and adapted to bear against wheel or pulley 20 if the spindle is pulled to the left in Fig. 4.

Spool 16 is adapted to be applied to and removed from the end of spindle 15, opposite spring 28, and to be rotated by and with said spindle. I have shown a bow-like spring 35 carried by spindle 15 and adapted to operate in a longitudinal groove 36 in said spindle, one end of said spring being secured to the spindle as at 37, (by suitable means such as solder), the opposite end of the spring being free to move in said groove. When the bore of the core of spool 16 is pushed upon the spindle the spring 35 will press on the spool and retain it on the spindle for positive rotation by the latter, and the spool may be readily pulled off the spindle. Instead of winding the strips back and forth along spools, as hereinafter explained, the strips may be wound in convolutions

upon cores 17, as in the nature of reels. The core 17 may have an internal longitudinal groove at 17^a adapted to receive the spring 35, when the core is pushed upon spindle 15, for positively rotating the core with the spindle. The core may have a longitudinal groove or recess in its periphery, indicated at 17^b, into which the end of the strip to be wound may be pushed for connecting the strip with the core, so that when the core rotates the strip will be wound thereon.

For rotating wheel or pulley 20 I have shown a pulley 38 rotative loosely on shaft 19 and connected with a pulley 39, a belt 40 passing over pulleys 20 and 38, and a belt 41 passing from pulley 39 to a pulley 42, which may be fast to wheel or pulley 10, whereby the desired speed and direction of rotation of spindle 15 may be derived from pulley 11 or drive shaft 2.

The strips 43 to be wound on spools 16 or cores 17 are to be guided to said spools or cores, and preferably between the ironing rolls 4 and 5. When such strips are to be folded, as for the production of "bindings," either having one or more folded portions, such as illustrated in Figs. 11 and 12, the strips may be fed through a suitable guide or folder of any wellknown character indicated at 44, adapted to fold the strips as they pass through the folder. The delivery end of said folder is shown located adjacent to the passes between the ironing rolls 4 and 5 (Fig. 3). If the strip is not to be folded, the guide 44 may have suitable shape, in a wellknown manner, for feeding the strip between the ironing rolls in a flat condition. In order to move the guide or folder 44 back and forth along the ironing rolls, and to cause the to and fro movements of such guide or folder by and in accordance with the rotation of spindle 15, I provide means described as follows: Guide or folder 44 is shown carried by a block 45 mounted to slide upon spaced guide rods 46, secured between standards 3. The base plate 44^a of guide 44 is shown adjustable upon block 45 by means of the slot 44^b in said plate receiving the screw 47 working in a threaded aperture in block 45. A projection 48 from block 45 receives the slotted or forked end 49 of a lever or arm 50, that is shown pivotally supported upon a screw or stud 51, shown carried by a block 52, secured upon a rod 53 secured to hangers 54 carried by bed 1. Means are provided for moving guide or folder 44 back and forth along adjacent to the ironing rolls 4 and 5, for which purpose I have shown a cam 55 receiving a stud or projection 56, carried by arm 50, said cam being secured upon shaft 57, shown journaled upon the hangers 54, depending from base 1, whereby rotation of said cam will cause arm 50 to reciprocate on its pivotal point 51. In order to cause

the guide or folder 44 to be reciprocated in accordance with the rotation of spindle 15, I have shown gearing interposed between said spindle and shaft 57 for rotating cam 55 in the required time. While any suitable gearing may be provided for such purpose I have shown mechanism as follows: A sprocket wheel 58 is secured upon spindle 15 and receives a chain 59 passing over a 10 sprocket wheel 60 that is mounted upon shaft 19 and is secured to a sprocket wheel 61. A chain 62 passes over wheel 61 and over a sprocket wheel 63 shown carried by a stud or shaft 64 projecting from a standard 3. 15 A sprocket wheel 65 secured to sprocket 63 receives a chain 66 that passes over a sprocket wheel 67 secured to shaft 57. When arm 18 is rocked the wheel 58 will travel on an arc described around the axis of wheel 20 60, the chain 59 remaining constant. By means of gearing interposed between spindle 15 and shaft 57, the cam 55 will be rotated at such speed as to cause the guide or folder 44 to move back and forth along 25 rolls 4 and 5 corresponding to each layer of strip 43 wound on spool 16, whereby such strip will be wound on the spool evenly from end to end thereof, notwithstanding the increasing diameter of the strip as it is wound 30 on the spool. Since the widths of strips 43 may vary, and since the guide or folder 44 derives its reciprocations directly from spindle 15, the pivot 51 may be adjusted along arm 50 to vary the movement of the latter 35 in accordance with the width of the strip to be wound. For such purpose I have shown arm 50 provided with spaced apertures 50^a adapted to receive the screw or pivot 51, the block 52 being shown provided 40 with correspondingly spaced threaded apertures 52^a receiving screw 51. By setting screw 51 farther from projection 48, the arm 50 will be given slower rocking movement for wider strips to be wound on spools 45 16, and by adjusting screw 51 nearer to projection 48 the arm 50 will be given relatively quicker rocking movements for narrower strips to be wound on the spools, and so on for intermediate widths of strips, the 50 screw 51 being adjusted in the apertures 50^a, 52^a, accordingly.

At 68, 69 is shown a suitable indicator for indicating the lengths of the strips wound on the spools or cores.

55 In accordance with my improvements, the strip 43 to be ironed and wound is passed through the guide or folder 44, and between the ironing rolls 4, 5, and is carried along the exterior of roll 5 and fastened to the 60 spool 16 or core 17, being preferably fastened near one end of spool 16 in a well-known manner, as by pasting the end of the strip to the spool. When the machine is started the rolls 4, 5, heat and iron the strip 65 passing between them, and at the same time feed the strip forwardly to the spool. The rotation of spindle 15 causes the strip to be wound on the spool, the rotation of said spindle imparting to the guide or folder 44 the desired reciprocatory motion, whereby 70 the strip is fed back and forth along and between the ironing rolls, causing the strip to be correspondingly wound back and forth along the spool, the strip bearing upon roll 5 as the strip is wound on the spool by 75 reason of the weight of arm 18, whereby the strip is caused to be snugly wound on the spool. Since the strip is fed forwardly between the ironing rolls with speed corresponding to the peripheral speed of said 80 rolls, the increasing diameter of the strip as it is being wound is accommodated by reason of slippage between the spindle rotating wheel or pulley 20 and the spindle, (due to the frictional coaction between the 85 pulley and flange 23) to overcome excess strain that would be put upon the convolutions of the strip were the spindle driven directly by wheel or pulley 20 without the interposed frictional devices, and since the 90 guide or folder 44 is reciprocated by the rotation of spindle 15, said guide or folder will be moved back and forth in accordance with the rotation of spindle 15 derived through the frictional devices, whereby the 95 strip will be guided back and forth along the spool in accordance with the speed of rotation of the latter, hence in accordance with the winding of the strip upon the spool, notwithstanding the increasing diameter 100 of the strip upon the spool. In other words, as the speed of rotation of the spool is such as to wind the strip thereon only as fast as the strip is fed by the rolls 4, 5, and as the movement of guide or folder 44 is 105 governed with the rotation of the spool, it follows that, as the spool will rotate slower as the diameter of the strip thereon increases, so also the reciprocations of guide or folder 44 will be slower as such diameter 110 of the spool increases. This is an important feature of my invention, since it enables the convolutions of each layer of the strip on the spool to be evenly laid from end to end of the spool, and substantially the same number of turns of the strip around the spool will be laid in each layer. This is particularly advantageous in spooling folded strips for bindings, especially where one edge of the strip is thicker than the other edge 115 owing to the character of folding of the strip in the folder 44.

When flat or unfolded strips are to be wound, as in the form of reels, a suitable guide 44, of any well-known form, may be 120 substituted for the strip folder, such flat strip being guided between the ironing rolls 4, 5, and attached to the core 17 that is mounted upon the spindle 15 in place of the spool, and arm 50 may be removed from 125 130

the machine, or from connection with projection 48, so that the guide 44 need not be reciprocated. When the fabric is wound upon cores, the reels so produced may be 5 slipped off the cores in a well-known manner.

My improvements enable the winding or spooling of all kinds of strips, from the more delicate fabrics, such as laces, to the 10 coarser fabrics, such as heavy binding material, without unduly straining the fabric, and at the same time winding the fabric smoothly and evenly on the spools or cores.

Changes may be made in the details of 15 construction and arrangement of parts shown and described, as the same may be varied, within the scope of the appended claims, without departing from the spirit of the invention.

Having now described my invention what I claim is:—

1. In a winding machine the combination of a spindle, a guide for a strip to be wound on the spindle, means to support the guide, 25 means operated by the spindle to move the guide back and forth relatively to the spindle in accordance with the rotation thereof, frictional means for rotating the spindle, and a roll opposing the rotation of the spindle 30 and coöperative with the goods being wound to retard rotation of the spindle as the goods thereon increase in diameter.

2. In a winding machine the combination of a spindle, a pair of ironing rolls to deliver 35 a strip to the spindle, a guide to direct the strip between said rolls, means movably supporting said guide, and means operated by the spindle to move the guide back and forth along said rolls to direct the strip between 40 the rolls for delivery of the strip back and forth along the spindle.

3. In a winding machine the combination of a spindle, frictional means for rotating the spindle, a pair of ironing rolls to deliver 45 a strip to the spindle, a guide to direct the strip between said rolls, means movably supporting said guide, means operated by the spindle by means of said frictional means to move the guide back and forth along the 50 rolls relatively to the spindle in accordance with the rotation thereof.

4. In a winding machine the combination of a spindle, a movable arm rotatively supporting the spindle, a driving wheel for the 55 spindle, frictional devices between said wheel and spindle for rotating the latter by the former, a guide to direct a strip to be wound on the spindle, a gear connected with the spindle, and means operatively connected

with said guide and actuated by said gear 60 for moving said guide back and forth relatively to the spindle in accordance with the rotation of the latter through said frictional devices.

5. In a winding machine the combination 65 of a spindle, a pair of ironing rolls, means to movably support the spindle, frictional means for rotating the spindle, a gear carried by the spindle for rotation thereby through said frictional means, a guide to direct a strip to be wound, means movably supporting the guide, and mechanism operatively connected with the guide and actuated by said gear for moving the guide back and forth through said frictional means in 70 accordance with the rotation of the spindle.

6. The combination of an arm, a wheel having a sleeve journaled in the arm, a spindle journaled in said sleeve, frictional means between the wheel and spindle for rotating 80 the latter within said sleeve, a guide to direct a strip to be wound, and mechanism operatively connected with said guide and spindle for moving the guide back and forth by and in accordance with the rotation of 85 the spindle through said frictional means.

7. The combination of an arm, a wheel having a sleeve journaled in the arm, a spindle journaled in said sleeve, a flange slidable on the spindle to frictionally coat with the 90 wheel to be driven by the latter, means to rotate the spindle by the flange, a spring coöoperating with the flange for frictional coöperation of the latter with the wheel, a stop on the spindle coating with the spring, 95 a gear on the spindle, a guide to direct a strip to be wound, means movably supporting the guide, and mechanism connected with the guide and operated by said gear for moving the guide back and forth by and in 100 accordance with the rotation of said spindle through said frictional means.

8. The combination of a spindle, a pair of ironing rolls, a guide to direct a strip between said rolls, a block supporting said guide, means movably supporting said block, an arm operatively connected with said block, means pivotally supporting said arm, a cam operatively connected with said arm, and gearing connecting said cam with said spindle whereby the guide will be reciprocated by and in accordance with the rotation of the spindle to direct the strip between the 110 rolls to the spindle.

Signed at New York city, in the county of 115 New York and State of New York, this 30th day of October, A. D. 1916.

OSCAR I. JUDELSHON.
